UNITED STATES PATENT OFFICE.

RALPH E. HART, OF GENEVA, INDIANA.

SAD-IRON.

1,098,572.

Specification of Letters Patent.

Patented June 2, 1914.

Application filed November 26, 1913. Serial No. 803,221.

To all whom it may concern:

Be it known that I, RALPH E. HART, a citizen of the United States, residing at Geneva, in the county of Adams and State 5 of Indiana, have invented certain new and useful Improvements in Sad-Irons, of which the following is a specification, reference being had to the accompanying drawings.

This invention relates to new and useful 10 improvements in sad-irons and more particularly to a self-heating sad-iron, the object of the invention being to provide a self-heating sad-iron having a fuel reservoir exposed to the heat produced at the burner 15 whereby the contents of the reservoir are vaporized, furthermore to provide means whereby the reservoir forms a heat guard to protect the hand of the operator and furthermore to provide a device whereby the burner 20 may be replaced when desired or necessary and is securely held in position when in use.

Another object of the invention is the provision of a self-heating sad-iron of the above character which will possess advantages in 25 points of efficiency and durability, is inexpensive to manufacture and at the same time is simple in construction and operation.

With the above and other objects in view the invention consists in the novel features 30 of construction and the combination and arrangement of parts to be hereinafter more fully described, pointed out in the claims and shown in the accompanying drawings, in which—

35 Figure 1 is a side elevation of my improved self-heating iron illustrating the manner of heating the generating pipes; Fig. 2 is a rear end elevation; Fig. 3 is a transverse sectional view; Fig. 4 is a longitudinal sectional view of the burner; Fig. 5 is a transverse sectional view of the feed pipe; Fig. 6 is a detail plan view of one end of the handle; Fig. 7 is a transverse sectional view through the supply tank; Fig. 8 is a 45 bottom plan view of the supporting plate; Fig. 9 is a detail plan view of one end of the base or shell; and Fig. 10 is a detail perspective view of the guard plate.

Referring more particularly to the drawings, 50 1 indicates the base or shell of the iron provided with a cavity forming a combustion chamber, suitable openings 2 being formed in the sides of the combustion chamber at the outer edge of the shell for the escape of products of combustion. The shell or base 1 is provided at its rear end with a vertical recess 3 and further provided upon

each side of the recess with upwardly projecting perforated ears 4. The base or shell 1 is provided at its forward end with a recess 5 which forms a vertical wall 6 having a threaded opening therein in which is arranged the set screw 7, the purpose of which will be hereinafter more fully set forth.

The heating portion of my improved sad-iron includes a plate 8 which is adapted to rest upon the upper edges of the shell 1. The plate 8 is provided at each end with outwardly projecting ears 8' and formed integral with said ears are the parallel up- 60 rights 10. The upper ends of the uprights 10 are arranged within the recessed ends of the handle member 11 and secured in position by means of the screws 12. Mounted upon the plate 8 and arranged between the uprights 10 is a reservoir 13 which is adapted to contain kerosene oil, gasoline or any other desirable fuel.

The feed pipe 14 connects with the interior of the reservoir 13 at one end thereof, as 65 shown at 15, said pipe thence extending rearwardly to the rear of the device, thence bent upon itself and engaged over the burner 16, thence running forwardly and then bent 70 upon itself and extending rearwardly to the connecting pipe 17, said connecting pipe having an angular portion 18 formed integral therewith in which is arranged a valve 19, said valve regulating the flow of gas into the rear end of the burner 16. The two longitudinal portions 20 of the pipe 14 are, 75 when the upper portion of the iron is arranged in position, adapted to be disposed beneath the spaced castings 21 within the base or shell 1 of the iron, said castings being suitably connected by means of a transverse portion 22.

Mounted upon the top of the reservoir 13 is a sheet of asbestos 23 which is securely retained in position by means of a metal plate 100 24, the plate being retained in position by means of the U-shaped brace member 25, the medial portion of which engages the upper face of the plate while the ends thereof are secured to the uprights 10 adjacent the upper ends thereof. In this manner, it will be apparent that the heat from the burner below the reservoir will be below the handle 11 so as not to interfere with the hand of the person when using the iron.

In placing the upper portion of the iron in position with respect to the base or shell 1, the spaced lugs 26 which are formed upon the rear of the plate 8 are engaged within

the perforated ears 4 and the outwardly projecting lug 8' at the forward end of the plate 8 is engaged within the recess 5 in the forward end of the shell and the set 5 screw 7 is tightened against one of the uprights 10 to prevent the removal of the upper portion of the shell. In order to fill the reservoir, I provide a suitable removable plug 27 which may be quickly and readily 10 removed to refill the reservoir when desired.

In the practical operation of my improved sad-iron, a small amount of alcohol is placed within the shell and lighted, the upper portion 15 of said sad-iron being tilted rearwardly, as illustrated in Fig. 1, and a U-shaped tin plate 29 is arranged above the heat so as to direct the same against the lower portion of the reservoir 13 and the supply tube 14 whereby the oil within said tube will be 20 readily generated into gas. After the oil within the tube has been generated into gas and the burner 16 lighted, the upper portion of the iron may be replaced and the heat from the burner will generate the oil within 25 the supply pipe into gas as fast as the oil flows into the same.

It will be noted that in forming the openings 28 within the burner 16, I prefer to form the openings so that a series of openings will 30 open substantially upon each side of the burner and the flame which issues from these openings will be directed upon the two longitudinal portions 20 of the feed pipe 14 so that the oil within the feed pipe will be 35 readily heated and generated into gas before being supplied to the burner. After the tubes 20 have been thoroughly heated from the alcohol which was burned within the shell, the heat from the burner 16 will 40 be sufficient to keep up the generation of gas within the tubes so that a continuous flow of gas will be supplied to the burner through the connecting pipe 17. It will be noted that when the tin plate 29 is not in use, the same 45 may be curved slightly and engaged over the handle, the central portion being disposed beneath the handle member 11 so that all of the parts of the sad-iron may be assembled when in use and thus eliminate an 50 accidental misplacement of any of the parts.

From the above description taken in connection with the accompanying drawings, it will be readily apparent that I have provided a simple and durable self-heating 55 sad-iron whereby a reservoir is provided to contain a sufficient amount of fuel and wherein the contents of the reservoir are gasified to maintain a sufficient heat within the base or shell of the sad-iron. It will be 60 apparent that in the beginning of the generation of the gas by placing alcohol or other fuel within the shell, the initial heating to the shell or case will be in progress so that

the base 1 may be quickly and readily heated after the burner 16 has been lighted. It 65 will be apparent that my device is extremely simple in construction and can be manufactured at a comparatively low cost.

While I have shown and described the preferred form of my invention, it will be obvious that various changes in the details of construction and in the proportions may be resorted to for successfully carrying my invention into practice without sacrificing any of the novel features or departing from the 75 scope of the appended claims.

What I claim is:—

1. A device of the class described including a base, having castings mounted therein, a plate adapted for removable engagement 80 with the base, uprights at each end of said plate, a handle secured to the upper ends of the uprights, a supply tank mounted upon the plate, and means secured to the uprights to retain the tank in position, a feed pipe 85 connected with the tank and forming a longitudinal coil, a burner connected with the feed pipe and arranged within the coil whereby the heat from the burner will gasify the oil before the latter passes into the 90 burner.

2. A device of the class described including a base, having perforated ears at one end, a plate having lugs removably engaged with said ears and adapted to rest upon the 95 base, spaced uprights at each end of the plate, a handle connecting the upper end of said uprights, a set screw carried by the forward end of the shell and adapted to engage one of said uprights to retain the plate upon 100 the shell, a supply tank carried by the plate, a supply pipe connected with the tank and forming a longitudinal coil, a burner arranged between the coils and connected with the pipe, said burner being provided with 105 openings and said openings being directed toward the longitudinal coils whereby the flame may gasify the oil therein.

3. A device of the class described including a hollow base member, a plate removably mounted upon the upper edges thereof, a tank carried by the plate, a burner disposed beneath said tank and adapted to be arranged within the base, and a feed pipe 110 connected with the tank and forming a longitudinal coil arranged upon opposite sides of the burner whereby the heat from the burner will gasify the oil before the latter passes into the burner.

In testimony whereof I hereunto affix my 120 signature in the presence of two witnesses.

RALPH E. HART.
